D. F. DALTON.

BUCKLE.

APPLICATION FILED JULY 13, 1917.

1,246,725.

Patented Nov. 13, 1917.

UNITED STATES PATENT OFFICE.

DANIEL F. DALTON, OF WATERBURY, CONNECTICUT, ASSIGNOR OF ONE-THIRD TO
JAMES CROMPTON, OF WATERBURY, CONNECTICUT.

BUCKLE.

1,246,725.

Specification of Letters Patent.

Patented Nov. 13, 1917.

Application filed July 13, 1917. Serial No. 180,276.

To all whom it may concern:

Be it known that I, DANIEL F. DALTON, a citizen of the United States, residing at Waterbury, in the county of New Haven 5 and State of Connecticut, have invented a new and useful Improvement in Buckles; and I do hereby declare the following, when taken in connection with the accompanying drawings and the characters of reference 10 marked thereon, to be a full, clear, and exact description of the same, and which said drawings constitute part of this application, and represent, in—

Figure 1 a plan view of a buckle constructed in accordance with my invention, with the coupling-piece detached.

Fig. 2 a reverse plan view of the same.

Fig. 3 a vertical sectional view of the parts in the engaged position.

20 Figs. 4 and 5 are underside views of modified forms of my invention, with the levers shown in the open position.

Fig. 6 an underside view of another modified form of my invention.

25 Fig. 7 a face view of the same.

This invention relates to an improvement in buckles and adapted for use in securing overshoes, overcoats, and various other purposes, the invention particularly relating to 30 the form and arrangement of spring, the object being to employ a wire spring which will also serve as means for connecting the lever to the body-member and to so form the parts that they will be interlocked with 35 each other; and the invention consists in the construction and arrangement of parts which will be hereinafter described and particularly recited in the claims.

In carrying out my invention as shown in 40 Figs. 1, 2 and 3, I employ a body-member 7 struck up from sheet metal and provided on opposite sides with perforations 8 by which it may be secured in place, although these means may be varied according to the purpose 45 for which the device is used. The body is formed with a projecting lip 9 at its forward end for the purpose as will hereinafter appear. The body is also formed with a rectangular opening 10, and at its rear end

50 with an ear 11 which is rolled to form a bearing for the ends of a spring 12. This spring 12 is formed from a piece of spring wire bent into U shape and at its outer end with a bow 13 which projects outward 55 through the rectangular opening 10 and

forms a connection for the lever 14 which is formed at its inner end with a bar 15 over which the hook extends, the end of the lever having a bearing on the casing on opposite sides of the opening 10. This device 60 is used in connection with a coupling-piece of any desired character. As shown in Fig. 1 of the drawings, this coupling-piece 16 is formed with perforated ears 17 by which it may be attached to a garment, and this 65 coupling-piece has a rectangular opening 18 forming a bar 19 which is engaged by the lever 14 in the usual way of buckles of this type. As shown, the central portion of the casing is thrown outward and the bar 19 is 70 similarly thrown outward so as to fit over the casing and so that the projecting lip 9 may rest upon the face of the coupling-piece which is thereby prevented from turning. The parts when interlocked are thus firmly 75 held together.

In Fig. 4 of the drawings, I have illustrated a modification of my invention in which the ends of the wire are turned outward and upwardly and engaged by ears 80 20 formed on the sides of the casing instead of at the end as shown in Fig. 2 of the drawings; and in this case a metal tab 21 may be connected with the rear end of the casing as a means for attaching the device to a garment. The arrangement and action of the 85 spring is the same as before described. In this connection it will be noted that the wire extends into notches 22 formed in the ears 20, but the lower portion of the ears may be 90 omitted as indicated in Fig. 5 of the drawings, which also shows the casing provided with a perforation 23 by which the device may be attached to a garment. It is thus apparent that the fixed end of the spring 95 100 may be connected with the body-member or casing in a variety of ways, that the casing may be connected with the garment in any desired manner, and it will also be understood without further illustration that the lever may be engaged with a coupling-piece 105 like that commonly employed with buckles of this type.

It is obvious, and as indicated in Figs. 6 and 7 of the drawings, that instead of forming the hook portion in the center of the wire, the wire 24 may have hooks 25 formed in its ends and the central portion 26 connected with the casing. In such construction instead of having the hooks project 110

through a centrally arranged perforation, they may be separated so as to extend through separately formed perforations 27. In this case, instead of forming the lever 14 with a rectangular opening to form a bar to be engaged by the hooks, the lever 14 may be formed on opposite sides with ears 28 to be engaged by the hooks 25 as shown in Fig. 7 of the drawings. By forming the spring from wire the body-member or casing may be formed from softer metal than is necessary when the spring is formed as an integral part of the body or casing.

I claim:—

1. A buckle comprising a body member formed with an opening, a wire spring connected with the body member and formed with a hook at the outer end projecting outward through the opening in the body member, and a lever connected with the hook portion of the wire projecting outward through the body member.

2. A buckle comprising a body-member the central portion of which is struck outward and formed at its outer end with a forwardly projecting lip, said body-portion also formed with a rectangular opening, a wire spring connected with the body member and formed with a bend at its outer end

projecting outward through said opening, a lever engaged with said spring, combined with a coupling member formed with a clearance opening through which the lever and tongue project, the tongue adapted to bear upon the face of the coupling-piece.

3. A buckle comprising a body-member or casing the central portion of which is struck outward and provided with a forwardly projecting lip, said body-member also formed with an opening, a wire spring connected with the body-member and formed with a bend at its outer end projecting outward through said opening, a lever provided at its end with a bar engaged by the said spring; combined with a coupling-member formed with a clearance opening and with a bar, the bar offset so as to rest upon the offset portion of the body-member and permit the lip to engage with the surface of the coupling-member.

In testimony whereof, I have signed this specification in the presence of two subscribing witnesses.

DANIEL F. DALTON.
